US00D721372S

(12) **United States Design Patent**
Kuroda et al.

(10) **Patent No.:** **US D721,372 S**
(45) **Date of Patent:** **** Jan. 20, 2015**

(54) **SCANNER**

(71) Applicant: **PFU Limited**, Kahoku-shi, Ishikawa (JP)

(72) Inventors: **Satoshi Kuroda**, Kahoku (JP); **Shuji Hashimoto**, Kanazawa (JP); **Ryoichi Yasukawa**, Kahoku (JP)

(73) Assignee: **PFU Limited**, Ishikawa (JP)

(**) Term: **14 Years**

(21) Appl. No.: **29/444,310**

(22) Filed: **Jan. 29, 2013**

(30) **Foreign Application Priority Data**

Dec. 12, 2012 (JP) 2012-030362

(51) **LOC (10) Cl.** **14-02**

(52) **U.S. Cl.**

USPC **D14/422; D14/453**

(58) **Field of Classification Search**

USPC D14/420, 422, 425, 462–470, 424, 389, D14/125, 399; D18/54, 55, 50, 53, 36–39, D18/14, 18–21, 49, 46, 52, 56, 51, 54.4; D13/164, 168; 358/400, 401, 448, 474, 358/486–488, 496, 497, 494, 473, 302, 468, 358/498; 382/312, 317, 321, 315; 400/613, 400/613.1–613.4, 690.1–690.4, 691–694, 400/88, 175; 399/107, 379, 380, 211, 212; 235/462.11, 462.41, 472.01, 470, 235/462.43; 361/680, 681; 378/177, 187, 378/188; 101/93.4, 269; 355/78; D24/165, D24/169, 186; 600/502, 503, 499, 494, 490, 600/485, 500, 492, 480, 493, 495, 479; 128/900; 16/286; 347/104, 109, 5; 271/186, 225, 126, 121, 137, 138

(57) **CLAIM**

The ornamental design for a scanner, as shown and described.

DESCRIPTION

FIG. 1 is a front perspective view of a scanner showing our new design;

FIG. 2 is a front view thereof;

FIG. 3 is a rear view thereof;

FIG. 4 is a left side view thereof;

FIG. 5 is a top plan view thereof;

FIG. 6 is an enlarged fragmentary view showing the display of the scanner; and,

FIG. 7 is another enlarged fragmentary view showing the display changing its angle.

The broken lines and portions contained within broken line are not claimed.

1 Claim, 6 Drawing Sheets
